DESIGN FOR A DRAWER UNIT FOR ROTARY STORAGE BINS

Arthur W. Mueller, Newton, Ohio, assignor to The
Frick-Gallagher Manufacturing Co., Wellston,
Ohio, a corporation of Ohio

Application September 22, 1944, Serial No. 115,403

Term of patent 14 years

(Cl. D80—1)

To all whom it may concern:

Be it known that I, Arthur W. Mueller, a citizen of the United States, residing at Shademoor Park, Newton, in the county of Hamilton and State of Ohio, have invented a new, original, and ornamental Design for a Drawer Unit for Rotary Storage Bins, of which the following is a specification, reference being had to the accompanying drawings, forming a part thereof.

Figure 1 is a front elevation of the drawer unit showing my new design.

Figure 2 is a top plan view.

Figure 3 is a side elevation.

Figure 4 is a perspective view with the individual drawers in closed position.

Figure 5 is a fragmentary perspective view showing one of the drawers open.

I claim:

The ornamental design for a drawer unit for rotary storage bins, as shown.

ARTHUR W. MUELLER.
